OVEREDGE SEWING MACHINE

Albert C. Peterson, Park Ridge, and Ned L. Walenberg and Clarence C. Smith, Chicago, Ill., assignors to Union Special Machine Company, Chicago, Ill., a corporation of Illinois

Application October 19, 1949, Serial No. 122,204

20 Claims. (Cl. 112—162)

1

This invention relates to sewing machines intended for industrial use and more particularly to machines of this type adapted to provide a line of overedge stitching of either the two-thread or three-thread types.

A primary object of the invention has been to provide a machine of the above indicated character which will operate at high speeds, in the neighborhood of or even above 5500 stitches per minute, without undue vibration and with a minimum of wear and servicing.

Another object has been to provide a machine of the character mentioned which is of compact and relatively simple construction and which may be easily operated. This phase of the invention is directed, in part, to the comfort and convenience of the operator and the ready observation of the stitch forming devices to insure correct formation of the desired seams.

Toward the foregoing ends, a feature of the invention resides in the provision of an enclosed housing at one side of the line of stitching which houses, in a lubricant-tight enclosure, all of the operating devices for the stitch forming elements and also the edge trimming mechanism usually provided in overedge sewing machines.

Another feature, related to the foregoing feature, is the provision of stitch forming instrumentalities and edge trimming mechanism which involves a plurality of operating shafts and rods or bars which are in parallel relation to each other and also to the main operating shaft of the machine.

A further feature is the provision of an overedge stitch forming member which is subjected to both longitudinal bodily movements and transverse oscillatory movements along and about an axis which is in a relatively high plane, preferably slightly above the work supporting surface. The means for operating this member, moreover, is such that a dwell or reduction in speed is provided toward one end of the stroke of reciprocity or bodily movement of the member. This is such that relative rapid bodily movement occurs, toward and away from the needle, when the thread engaging portion of the member is above the work support and a slower bodily movement occurs when such thread engaging portion is below the work support. Better stitch formation results from this. It also permits the machine to be used more advantageously for the stitching of heavier materials, since the active end of the stitch forming member may be carried a greater distance from the throat plate in its movements around and over the edge of the work.

2

In attaining the foregoing objects a still further feature of the invention resides in the relative arrangement of the various stitch forming instrumentalities. This includes not only the provision of two looper rods parallel with the main shaft of the machine, and each arranged to be reciprocated longitudinally of its axis, but also the positioning of one of these rods above and behind the other. The upper rod, moreover, is given oscillatory movements as well as reciprocatory movements. Both rods are operated across the line of feed and all of the operating mechanism for both rods is located to the right of the needle or the line of stitching. The operating means for the needle is similarly located. All of these features contribute to the production of uniform stitches, with a minimum risk of incomplete stitch formation, and in such a manner that the point of stitch formation is visible without requiring the operator to assume an awkward position.

Other objects, features, and advantages of the invention will appear from the detailed description of an illustrative form of the same which will now be given in conjunction with the accompanying drawings, in which:

Fig. 1 is a front elevational view of the machine, a portion of the work supporting plate being broken away to show normally concealed parts;

Fig. 2 is a longitudinal section through the machine, taken along its axis;

Fig. 3 is a detail view, in vertical section, illustrating a modification in which the overedge, threaded looper is replaced by a spreader;

Fig. 4 is a horizontal section through the machine, taken along the broken line 4—4 of Fig. 2;

Fig. 5 is a view partially in end elevation and partially in vertical section, taken substantially along the line 5—5 of Fig. 1;

Fig. 6 is a detail view in section, through the presser bar tensioning means, taken along the line 6—6 of Fig. 5;

Fig. 7 is a vertical sectional view through the machine, taken along the line 7—7 of Fig. 2;

Fig. 8 is a detail view, in vertical section along the line 8—8 of Fig. 4, showing certain of the operating connections in the machine;

Fig. 9 is a similar detail view, in section along the line 9—9 of Fig. 4, showing additional operating connections;

Fig. 10 is a detail view, partly in plan and partly in horizontal section, showing the construction and mounting of the presser foot; and

Fig. 11 is a diagrammatic view illustrating the

relative positions of the stitch forming instrumentalities at different points in the cycle of operation of the machine.

Referring now to the drawings, the illustrative machine has a main frame a large portion of which is in the form of an enclosed housing, including a vertical wall structure 10 (Figs. 1 and 2), a bottom 11 secured in oil-tight relation to the wall structure in any suitable way as by means of screws, and a top cover 12 disposed on a slope, as shown, and secured to the vertical walls by screws 13. The left hand end of the housing (Fig. 2) is closed by a substantially vertical wall 14 from the lower end of which an extension 15 projects beneath the work supporting member or cloth plate 16 of the machine. Between the extension 15 and the work supporting member 16, a partially enclosed space is provided for certain of the stitch-forming and work-feeding devices to be hereinafter described. An upward extension 17 at the rear of the lateral extension 15 serves, in part, to support the work supporting member 16, which is pivotally carried by a pin 18. This permits the work support to be swung outwardly to provide access to the mechanism normally beneath the work support, for threading the loopers and inspecting and adjusting various parts. It also permits the seaming of the edge of circular work. On a pivot pin 19 there is swingably mounted a partial cover member 20 (Figs. 1, 2 and 4) arranged normally to substantially enclose the major portion of the work feeding devices. Member 20 has an outwardly projecting ear 21 which fits between a pair of lugs 22, formed on the member 17, which carry the pivot pin 19. The cover member 20 is left in its normal projecting position when circular work is being seamed. Toward the forward end of the lateral extension 15 an upwardly extending pedestal 23 is provided to support a portion of the trimmer mechanism, as will be explained, and to assist in partially enclosing the mechanism. To the top of the pedestal is secured a throat plate 23a which complements the work supporting member 16.

A main operating shaft 24 extends longitudinally in a horizontal direction through the lower portion of the main housing. Shaft 24 is formed in two sections, for assembly purposes, these having telescoping ends clamped together by screws 24a (Fig. 2). The shaft projects from the housing at both ends. Adjacent its left end (Fig. 2) it is journaled in a bushing 25, mounted in a boss projecting from wall 14, while at an intermediate point it is journaled in a bushing carried by a transverse wall 26 extending between and formed integral with the front and rear walls of the housing. Adjacent its right end, the main shaft is supported by a ball bearing 27 carried by a bushing 28 mounted in the right end wall of the housing. Bushing 28 preferably has a radially extending flange at its outer end by means of which it may be secured, by screws or the like, to the wall of the housing. To the outer end of the shaft 24, which projects beyond the bushing 28, there is secured a combined handwheel and pulley 29.

The stitch-forming instrumentalities include a curved needle 30 which, as best shown in Fig. 5, is carried by a head 31 at the upper end of an arm 32 secured to a rock shaft 33. The latter is journaled in a bushing 34 which extends through the wall 14 of the housing. Within the housing a split sleeve 35 (Fig. 8) is se-

cured to the shaft 33, this sleeve having a forwardly projecting arm 36 which is pivotally connected with a pitman 37 having, at its lower end, a strap 38 cooperating with a cylindrical crank portion 39 of the main shaft 24. This arrangement is such that upon rotation of the shaft 24, the shaft 33 will be rocked to carry the curved needle from the position indicated in Fig. 5 to a position in which the eye of the needle is beneath the work support and in the path of an under looper now to be described.

In the machine illustrated, an under looper 40 (Fig. 2), of generally U-shaped form at its active end and provided with a thread carrying eye, is secured by a set screw 41 to the outer end of a reciprocating, shaft-like rod 42. This rod is mounted for longitudinal sliding movement in a bushing 43 carried by the wall 14 of the housing and a bushing 44 carried by the intermediate wall 26. Between the bushings 43 and 44 there is secured to the rod a block 45 (Figs. 2 and 7) having a horizontally extending trunnion arranged for pivotal connection with a link 46 the opposite end of which is pivotally connected at 47 to the lower end of an arm 48. The latter is integral with and extends downwardly from a sleeve 49 rockably mounted on a stationary shaft 50 carried by the front and rear walls of the housing. Sleeve 49 has a laterally extending arm 51 providing a split collar to receive and clamp a ball pin 52. A screw 53 serves to clamp the ball pin in the split collar. Cooperating with the ball surface of the pin is a strap 54 carrying a downwardly extending rod 55 connected with another strap 56 arranged to cooperate with a spherical eccentric portion 57 of the main shaft 24. Rod 55 and straps 54 and 56 are arranged to provide an extensible link for connecting the eccentric or crank with the ball pin 52. Through the connections described, the rod 42 and hence the under looper 40 will be reciprocated upon each revolution of the main shaft.

An overedge looper 58 (Fig. 2), which may also be provided with a thread carrying eye, is secured in any suitable way to a shaft-like rod 59 which is adapted to receive both oscillatory and reciprocatory movements. As shown in Fig. 3, the thread carrying looper may, if desired, be replaced by a forked spreader 58a adapted to be secured to the oscillatory and reciprocatory rod 59. Similarly, the under looper 40 may be replaced, if desired, by a spreader having a forked end, like that of the element 58a, in which case the overedge member should be a thread carrying looper. The coordinated operation of the stitch-forming elements will be hereinafter described in relation to Fig. 11.

The rod 59 is supported by a bushing 60, carried by the wall 14 of the housing, and by another bushing 61 carried by the wall 26 (Figs. 2 and 4). For imparting oscillatory movements to the rod, its inner end is provided with a crank arm 62 from which projects a ball pin 63 cooperating with a strap 64 at the upper end of a pitman 65. The lower end of this pitman carries a strap 66 cooperating with a spherical eccentric portion 67 of the main shaft 24. It will be apparent that upon rotation of the shaft 24, the arm 62 together with rod 59 and looper 58 will be oscillated, the arrangement being such that the active end of the looper is carried from a point below the work support to a point well above the latter.

Longitudinal reciprocations are imparted to the rod 59 in the following manner. A block 68 (Figs.

2 and 9 is freely mounted on the rod between two collars 69 which are clamped to the rod. This arrangement is such that relative rotation may take place between the block and the rod, but the two elements partake of longitudinal movements together. Projecting rearwardly from the block 68 is a trunnion or pin 68a to which is pivotally connected one end of a link 70, the other end of which is pivotally connected to the lower end of an arm 71 having a hub or sleeve mounted for free rocking movement on the fixed shaft 50 (Fig. 7). Intermediate the ends of the arm 71 there is pivotally connected thereto, at 72, one end of a pair of links 73 pivotally attached at their upper ends to an arm 74 extending upwardly and toward the right (Fig. 2) from a sleeve 75 which is mounted for rocking movement upon a fixed shaft 76. Sleeve 75 is held against axial movement along the shaft 76 by a pair of fixed collars 77 (Fig. 9). The pivot pin 78, which serves to connect the links 73 with the arm 74, is of greater length than required for this purpose. As shown in Fig. 4 it preferably passes through the arm 74 into a parallel companion arm 79 extending outwardly from the sleeve 75. It is held fixed in the arm 74 by a screw 80. Adjacent its outer end pin 78 is provided with a ball 81 which cooperates with a strap 82 (Figs. 2 and 9) connected by a rod 83 with one side of a strap 84 surrounding a spherical eccentric 85 carried by the main shaft 24. It will be apparent that upon each revolution of the shaft 24, the rod 83 will be reciprocated vertically and will, through the linkage explained, reciprocate the block 68 together with the rod 59. As will be explained more fully hereinafter, these operating connections are such that a relatively rapid longitudinal movement is imparted to the rod 59 adjacent one end of its stroke and a slower movement is imparted to it toward the other end of its stroke.

Referring now to the diagram of Fig. 11, there is indicated the relative timing of the three stitch forming instrumentalities, i. e., curved needle 30, under looper 40, and overedge looper 58. The numbered positions indicated for the points of these three elements correspond with 30° increments of rotation of the main shaft. The three elements are illustrated in their number 9 positions, in which the curved needle has passed well below the work and is approaching the lower end of its stroke. The underlooper is at the extreme left hand end of its stroke and the overedge looper is being retracted from a position above the work to one beneath it. As the needle descends further, the under looper will start its movement toward the right and it will continue such movement during most of the return stroke of the needle. It will pass through the loop of the needle thread upon the initial upward movement of the needle, i. e., between the 11 position and the 0 position. The thread carried by the under looper will thus be carried through the needle thread loop and will be passed into the path of the overedge looper 58. The latter will then pass its thread through the loop of the under looper thread as the parts are moving from the 1 to the 2 position. As the cycle continues, the overedge looper thread will be carried around the edge of the work and up over the latter to the 6 position. As the overedge looper is moving from the 5 to the 6 position the needle will be on its downward movement again and will pass through the loop of the overedge looper thread. This cycle will be repeated continuously during

the operation of the machine to form a three-thread overedge line of stitching. It is understood, of course, that the work will be advanced between successive stitches by the mechanism to be hereinafter described.

If desired, a two-thread overedge stitch may be formed by substituting a spreader for one or the other of the loopers 40 and 58. If a spreader, which is in effect a looper with a thread engaging fork instead of a thread carrying eye, is substituted for the under looper this will pick up the loop of the needle thread and carry it into the path of the overedge looper, so that the latter with its thread will pass through the loop of the needle thread. Otherwise the operation is the same as in the formation of a three-thread stitch. Similarly if the overedge looper is replaced by a spreader, the forked end of this spreader will merely seize the thread of the under looper, when the latter is between the 1 and 2 positions, and will carry the under looper thread upwardly and over the work into the path of the needle which will then pass its thread through the loop of under looper thread.

It will be noted that the path of the point of the overedge looper from point 3 to point 6 and and then back to point 9 is inclined at a greater angle to the vertical than the balance of its path from point 9 to point 0 and back to point 3. A dwell or slower movement of the overedge looper, so far as longitudinal reciprocation of the rod 59 is concerned, is thus clearly indicated. The more rapid movement during the first mentioned half of the cycle permits a greater clearance to be provided between the overedge looper and the edge of the cloth plate without giving the rod an unduly long stroke. As previously indicated, this has various advantages, including the possibility of handling heavier work.

Any suitable means may be employed for feeding the work past the stitch forming point. Preferably this is of the differential type, involving a main feed dog 86 (Figs. 4 and 5) and a differential feed dog 87. These are given different feed strokes and suitable mechanism for this purpose will now be briefly described. Feed dog 86 is secured by a screw 86a to the forward end of a main feed bar 88 which is forked at its rearward end to straddle a square block 89 rockably mounted on a fixed shaft 90 carried by the main frame. At its forward end the feed bar 88 is also forked to straddle a square block 91 (Fig. 2) mounted on an eccentric portion of the main shaft 24. This arrangement is such that upon rotation of shaft 24 the forward end of the feed bar will be lifted and lowered to impart corresponding movements to the feed dog. Feed stroke and return movements are imparted to the latter by means of a strap 92 cooperating at its forward end with an eccentric portion 93 (Fig. 2) adjacent the outer end of the main shaft 24. The various parts are held in assembled relation on the main shaft by a nut 94. At its other end the strap 92 is provided with an opening which snugly receives a pin 95 extending laterally from the feed bar 88. It will be understood that suitable openings are provided in various intervening parts to permit the free passage of this pin. A nut 96 holds the various parts in assembled relation. It will be seen that upon rotation of the main shaft 24 the eccentric 93 will impart longitudinal movements to the feed bar for the feed and return strokes thereof. The vertical throw of the strap 92 by the eccentric 93 will, of course, be ineffective and will simply rock

the strap about pin 95, since the vertical position of the feed bar is controlled by the eccentric within the square block 91.

The desired four motion movements are similarly imparted to the differential feed dog 87. This is secured by a screw 87a to the forward end of a feed bar 97 which is forked at its rearward and forward ends to straddle the square blocks 89 and 94, so that lifting and lowering movements are imparted to the differential feed dog 10 simultaneously with the main feed dog. The feed and return movements are imparted to the differential feed dog by a strap 98 the forward end of which surrounds an eccentric 99 on the main shaft 24. At its rearward end the strap 98 is 15 apertured to receive a pin 100 extending laterally from the auxiliary feed bar. A nut 101 serves to maintain the parts in assembled relation. It will be understood that longitudinal movements will be imparted to the feed bar 97 upon rotation 20 of the eccentric 99 to provide the desired feed and return movements of the differential feed dog.

Should it be desired to vary the strokes of either of the feed dogs this may be readily accomplished by substituting different eccentrics 93 and 99. These are preferably in the form of small annular members which may be freely applied to or removed from the shaft 24, but are suitably keyed thereto in a predetermined angular position. They 30 may be removed and replaced upon the simple removal of the nut 94.

For holding the work against the throat plate, and cooperating with the feed dogs in advancing the work along the line of stitching, is a presser foot 102. This may be of any suitable form, but in the preferred embodiment is of the type shown in Fig. 10. It is pivotally mounted by means of a pin 103 at the lower end of a downwardly curved, horizontally disposed presser bar or arm 104. Pin 103 has screw threaded engagement with an opening in the presser bar to retain the foot 35 thereon. Bar 104 is secured, by screws 104a, to a short forwardly extending arm 105 (Figs. 4 and 5) integral with a yoke 106 pivotally mounted 40 on a pin 107. The latter is carried by a member 108 which fits between two branches of the yoke 106 and has an integral split collar 109 by means of which it is secured to a rock shaft 110 mounted in suitable bearings in lugs 111 and 112 extending rearwardly from the main frame. An arm 113 is freely mounted on the shaft 110 and is normally urged upwardly (Fig. 4) or in a clockwise direction (Fig. 5) by a spring 114. The hub-like portion of the arm 113 which surrounds the shaft 110 has a downward extension 115 adapted to cooperate with the end of a set screw 116 mounted in a downwardly and laterally extending arm 117 of the collar 109. When the arm 113 is rocked downwardly, or in an anti-clockwise direction, by any suitable means, such as a rod or chain connected with an eyelet 118 at the outer end of the arm, the projection 115 will engage the end of the screw 116 and rock the collar together with the shaft 110 and will cause 50 the presser bar 104 to be rocked anti-clockwise to lift the presser foot.

For normally urging the presser foot against the work, a yoke 118 is arranged to straddle the presser bar at an intermediate point. This yoke is carried at the lower end of a rod 119 slidably mounted in a sleeve 120 which is, in turn, slidably mounted in a lug 121 extending outwardly from the wall 14 of the frame. A pin 122 extending inwardly into the path of the sleeve 120,

from the lug 121, cooperates with a T-slot in the sleeve 120. When the pin is aligned with the vertical portion 123 of the T-slot the sleeve is free to be shifted axially of the lug. However, if the sleeve is rotated slightly in either direction to place the pin 122 in one of the cross arms formed by the top 124 of the T-slot, the sleeve will be locked against axial movement in the lug. Surrounding a reduced portion of the rod 119 within the sleeve 120 is a spring 125. The lower end of this spring cooperates with the shoulder provided by the enlarged lower portion of the rod, while the upper end cooperates with a washer 126 carried at the upper end of a bore within a screw threaded member 127 which has threaded engagement with the sleeve 120. By turning of the member 127, through the knurled thumb piece 128, the axial position of the member in relation to sleeve 120 may be varied to adjust the tension of the spring. An enlarged head 129 is provided at the upper end of the rod 119 to limit the downward movement of the rod under the influence of the spring when the yoke 118 is disengaged from the presser bar, in the manner to be explained.

By turning the sleeve 120 to bring the vertical slot 123 in line with the pin 122, the tension on the spring 125 may be fully released and the yoke 118 may then be readily disengaged from the presser bar 104. This will permit the latter to be swung outwardly about the pivot pin 107 through any desired angle, up to about 180°. The presser foot 102 is thus carried away from the throat plate and threading of the loopers is facilitated. Also, the throat plate may then be readily removed for inspection and adjustment of the parts beneath it.

As shown in Fig. 10, the presser foot is preferably provided with a stitch finger 130 which extends over a recess or cut-out 131 in one side of the presser foot adjacent the point of stitch formation. The stitch finger is preferably made adjustable transversely of the presser foot. For this purpose it is formed on a member 132 having an elongated slot 133 cooperating with the shank of a screw 134. Member 132 is of U-shaped form at its outer end to accommodate the blades of the trimming mechanism now to be described.

A stationary blade 135 is suitably mounted, in an inclined position in a plane parallel with the line of stitching, on an adjustable block 136 carried by the pedestal 23. The blade 135 may be clamped in the block in any suitable way as by means of a bolt 137 extending through the block and having an enlarged slotted head at its outer end which holds the blade against the face of the block. A nut 138 holds the bolt in clamping position. Block 136 is mounted for adjustment in a direction transverse to the line of stitching by supporting the same in a groove or rectangular recess formed in the forward face of the pedestal (Fig. 5). A guide plate 139, secured by a screw 140 to the forward face of the pedestal, serves to assist in retaining the block in the recess. A screw 141, the shank of which cooperates with a slot 142 extending through the block 136 at the outer end thereof, serves to clamp the block in any position desired. Adjustment of the block may be effected, when the clamping screw 141 is loosened, by turning an adjusting screw 143, the enlarged head of which engages the end of the block and the shank of which is threaded into a suitable opening in the pedestal 23. It will be apparent that the means described will permit ad-

justment of the blade 135 in a direction transverse to the line of stitching to the position desired, depending upon the width of the over-edge stitching selected. The vertical position of the blade may be adjusted by loosening the clamping means 137, 138.

Cooperating with the stationary trimmer blade is a movable blade 144 (Figs. 1, 4 and 5) which is preferably substantially L-shaped in cross-section. The cross-section of the blade is best shown in Fig. 4. This blade is adjustably mounted in an inclined groove provided in the outer face of a block 145 and a corresponding inclined groove in a collar 146. The block and collar are mounted on a head 147 at the outer end of an arm 148. A screw 149 (Fig. 1) serves to clamp the collar 146 and block 145 to the head. Screw 149, for this purpose, cooperates with a nut 150 mounted in a channel provided in the head 147. This channel (Fig. 5) extends in a direction transverse to the line of stitching. Substantial clearance may be provided between the nut and the top and bottom surfaces of the channel but the latter serve to prevent rotation of the nut. Block 145 preferably has an inward extension 151 cooperating with a guide slot in the forward face of the head 147. This guide slot is parallel with the channel and may extend into the latter. The arrangement is such that upon the loosening of the screw 149 the block 145 may be shifted in a direction transverse to the line of stitching and the blade 144 may also be adjusted upwardly or downwardly along the inclined groove above mentioned. Tightening of the screw serves to retain the parts in adjusted position. Proper coaction between the stationary and movable trimmer blades is thus insured for any selected width of overedge stitching.

The trimmer operating arm 148 is integral with or otherwise secured to the outer end of a shaft 152 (Fig. 4) journalled in a bushing 153 extending through the wall of the housing. At its inner end, within the housing, the shaft 152 has clamped thereto a member 154 (Fig. 8). This member has a downwardly and rearwardly extending arm 155 which carries a strap 156 at its lower end, cooperating with a ball pin 157. The latter extends transversely from a pitman 158 having a strap 159 (Fig. 2) surrounding a cylindrical eccentric or crank portion 160 of the main shaft 24. It will be apparent that upon rotation of the shaft 24 the shaft 152 will be oscillated to carry the trimmer arm 148 and blade 144 downwardly and then upwardly about the axis of shaft 152. A guide block 161 (Figs. 1 and 4) is secured to the outer face of the wall 14 by screws 162 to provide a hard bearing surface for the adjacent end of the head 147, as the latter is reciprocated.

Within the main housing of the frame, a body of lubricant 163 (Fig. 2) is provided and this is adapted to be whipped into a fine mist or spray by a disc 164 having a hub 165 clamped to the main shaft 24, adjacent the bearing 27. It will be noted from Fig. 2 that the disc 164 is the only part of the mechanism within the housing which dips into the oil. This makes for quick starting of the machine, since the only resistance to turning of the main shaft, so far as the lubricant is concerned, is the small frictional resistance between the lubricant and the relatively smooth faces of the disc. The latter, upon rotation at the high speeds of operation of the machine, will completely fill the housing

with a fine mist or spray. Some of the lubricant in this form will be carried directly to certain of the wear receiving surfaces, while some will collect on the top closure 12 and will drip from the latter onto various bearing surfaces. Suitable downwardly extending projections may be provided on the cover 12, if desired, to facilitate such delivery of the lubricant to special points. Openings may be provided in the tops of the various sleeves, bearings, and the like to permit the lubricant to reach the pins or shafts about which relative rotation takes place.

The only mechanism outside of the enclosed housing which requires lubrication is the work feeding mechanism. For the lubrication of this, 15 a pair of tubes 166 is provided through the wall 14 (Fig. 7). These tubes carry wicking 167 and 168. The portion of this wicking which extends downwardly within the enclosed housing, as 20 shown in Figs. 7 and 8, will collect lubricant from the mist generated in the housing, including some which may trickle down the inner surface of the wall 14. This lubricant will then be delivered by the wicking to the work feeding mechanism outside of the housing. Wicking 167 is preferably 25 extended along the upper surface of the pitman 98 from which it is readily delivered to the various bearing surfaces within the partial closure 20. Wicking 168 may be extended in the opposite 30 direction to supply lubricant to the rear bearing surfaces of the block 89. Suitable openings may be provided in the various members to enable delivery of adequate lubricant to the several bearing surfaces.

Excess lubricant dripping from the work feeding mechanism accumulates in a sump formed beneath the latter and is returned to the main supply within the housing, by gravity. A screen 169 and a felt filtering member 170 are provided 35 at the bottom of the lubricant collecting sump to remove particles of lint, filler, and the like from the lubricant before it is returned, through a passage 171 in the extension 15, to the interior 40 of the housing.

It will be understood that various accessory 45 devices, such as thread guiding and controlling means, including thread tensioning devices, will be provided for the supply of thread to the several stitch forming instrumentalities. Since the details of these devices form no part of the present invention, they need not be described. A cover member 172, having a portion extending vertically beneath the cloth plate and a forwardly inclined portion secured by a screw 173 to a part 50 of extension 15, serves to conceal and protect 55 against the accumulation of dust, certain of the parts outside of the main housing. The trimmer mechanism, however, is disposed in front of this cover member to render it accessible and to enable the cover member to deflect the trimmings 60 away from the mechanism.

While an illustrative embodiment of the invention 65 has been disclosed in considerable detail, it will be understood that numerous changes may be made in the construction and arrangement of the various parts without departing from the general principles and scope of the invention. In the claims, which follow, the term "looper" 70 should be construed as embracing both a member having a thread receiving eye and one having a loop engaging end serving as a spreader.

What we claim is:

1. In an overedge sewing machine, a plurality of stitch forming elements including a needle, an under looper and an overedge element, a plurality

of parallel shaft-like members each carrying one of said elements in fixed relation thereto, means for supporting said shaft-like members and retaining their axes in fixed relation, a main drive shaft, and connections from said drive shaft to said element carrying members for operating said elements in properly timed relation to effect overedge stitching, said connections being arranged to impart both oscillatory and reciprocatory movement to at least one of said members.

2. In an overedge sewing machine, a plurality of stitch forming elements including a needle, an under looper and an overedge element, each of said elements having a thread engaging portion, a plurality of constantly parallel shaft-like members each carrying one of said elements in fixed relation thereto, a main drive shaft parallel with said plurality of members, and connections from said drive shaft to said element carrying members for operating said elements in properly timed relation to effect overedge stitching, said connections being arranged to impart to the thread engaging portion of one of said elements a movement having a component transverse to and a component parallel with the axis of the related shaft-like member.

3. In an overedge sewing machine, a plurality of stitch forming elements including a needle, an under looper and an overedge element, a plurality of parallel shaft-like members each carrying one of said elements in fixed relation thereto, a main drive shaft and connections from said drive shaft to said element carrying members for operating said elements in properly timed relation to effect overedge stitching, said connections being arranged to impart to one of said element carrying members oscillatory movements only and to another of said members reciprocatory movements only and to another of said members combined oscillatory and reciprocatory movements about and along a fixed axis.

4. In an overedge sewing machine, a plurality of stitch forming elements including a needle, an under looper and an overedge element, a plurality of parallel shaft-like members each carrying one of said elements in fixed relation thereto, a main drive shaft, and connections from said drive shaft to said element carrying members for operating said elements in properly timed relation to effect overedge stitching, said connections being arranged to impart to the needle carrying member oscillatory movements only and to said under looper carrying member reciprocatory movements only and to said overedge looper carrying member combined oscillatory and reciprocatory movements about and along a fixed axis.

5. In an overedge sewing machine, a plurality of stitch forming elements including a needle, an under looper and an overedge element, each of said elements having a thread engaging portion, a plurality of parallel shaft-like members each carrying one of said elements in fixed relation thereto, means for trimming the edge of the work adjacent the point of stitch formation, said means comprising a movable trimmer blade, a shaft parallel with said shaft-like members for operating said movable trimmer blade, a main drive shaft, and connections from said drive shaft to said element carrying members for operating said elements in properly timed relation to effect overedge stitching, said connections being arranged to impart to the thread engaging portion of one of said elements a movement having a component transverse to and a component parallel with the axis of the related shaft-like member.

and connections from said main shaft to said shaft for operating said trimmer blade.

6. In an overedge sewing machine, a plurality of stitch forming elements including a needle, an under looper and an overedge element, a plurality of shaft-like members each carrying one of said elements in fixed relation thereto, the vertical planes containing the axes of said members being in parallel relation to each other, a main drive shaft parallel with all of said vertical planes, said drive shaft having a plurality of eccentric means thereon, and connections from said eccentric means on said drive shaft to said element carrying members for operating said elements in properly timed relation to effect overedge stitching, said connections being arranged to impart both oscillatory and reciprocatory movement to at least one of said members.

7. In an overedge sewing machine, a plurality of stitch forming elements including a needle, an under looper and an overedge element, a plurality of constantly parallel shaft-like members each carrying one of said elements in fixed relation thereto, a main drive shaft parallel with said plurality of members, said drive shaft having a plurality of eccentric means thereon, certain of said eccentric means having spherical peripheral surfaces and another having a cylindrical peripheral surface, and connections from said eccentric means on said drive shaft to said element carrying members for operating said elements in properly timed relation to effect overedge stitching.

8. In an overedge sewing machine, a plurality of stitch forming elements including a needle, an under looper and an overedge element, a plurality of constantly parallel shaft-like members each carrying one of said elements in fixed relation thereto, a main drive shaft, and connections from said drive shaft to said element carrying members for operating said elements in properly timed relation to effect overedge stitching, said connections being arranged to impart to the needle carrying member oscillatory movements only and to said under looper carrying member reciprocatory movements only and to said overedge looper carrying member combined oscillatory and reciprocatory movements, said connections for imparting reciprocatory movements to said overedge looper including means for imparting more rapid movements toward one end of the stroke thereof than toward the other end.

9. An overedge looper mechanism comprising a looper carrying rod mounted for axial reciprocation and for oscillation along and about a fixed axis, a main drive shaft parallel with said looper carrying rod, a plurality of eccentric means on said drive shaft, connections from one of said eccentric means to said looper carrying rod for oscillating the same, and connections from another of said eccentric means to said looper carrying rod for reciprocating the same.

10. An overedge looper mechanism comprising a looper carrying rod mounted for axial reciprocation and for oscillation along and about a fixed axis, a main drive shaft parallel with said looper carrying rod, a plurality of eccentric means on said drive shaft, connections from one of said eccentric means to said looper carrying rod for oscillating the same, and connections from another of said eccentric means to said looper carrying rod for reciprocating the same, said last mentioned connections including means for producing more rapid axial movement of said rod

toward one end of its stroke than toward the other end.

11. An overedge looper mechanism comprising a looper carrying rod mounted for axial reciprocation and for oscillation along and about a fixed axis, a main drive shaft parallel with said looper carrying rod, a plurality of eccentric means on said drive shaft, connections from one of said eccentric means to said looper carrying rod for oscillating the same, and connections from another of said eccentric means to said looper carrying rod for reciprocating the same, said last mentioned connections including a toggle arranged to produce more rapid axial movement of said rod toward one end of its stroke than toward the other end.

12. An overedge looper mechanism comprising a looper carrying rod mounted for axial reciprocation and for oscillation along and about a fixed axis, a main drive shaft parallel with said looper carrying rod, a plurality of eccentric means on said drive shaft, connections from one of said eccentric means to said looper carrying rod for oscillating the same, and connections from another of said eccentric means to said looper carrying rod for reciprocating the same, said connections being such as to provide for reversal of direction of the oscillatory and reciprocatory movements at substantially the same time and to cause said looper to traverse substantially the same path in both directions.

13. An overedger comprising a frame having an enclosed, lubricant-tight housing, a main drive shaft extending through said housing and projecting therefrom at both ends, means mounted on one end of said shaft for driving the same, stitch-forming means comprising a needle, an underlooper and an overedge looper outside of said housing, a plurality of shaft-like members extending through a wall of said housing, each of said plurality of members being connected in fixed relation to one of said stitch forming means, and connections within said housing from said drive shaft to each of said plurality of members for imparting stitch-forming movements to said means.

14. An overedger comprising a frame having an enclosed, lubricant-tight housing, a main drive shaft extending through said housing and projecting therefrom at both ends, means mounted on one end of said shaft for driving the same, stitch-forming means comprising a needle, an under-looper and an overedge looper outside of said housing, a plurality of shaft-like members extending through a wall of said housing, each of said plurality of members being connected in fixed relation to one of said stitch forming means, and connections within said housing from said drive shaft to each of said plurality of members for imparting stitch-forming movements to said members, said connections being arranged to impart bodily reciprocation to said needle and underlooper and a combined oscillation and bodily reciprocation to said overedge looper.

15. An overedger comprising a frame having an enclosed, lubricant-tight housing, a main drive shaft extending through said housing and projecting therefrom at both ends, means mounted on one end of said shaft for driving the same, stitch-forming means comprising a needle, an underlooper and an overedge looper outside of said housing, a plurality of shaft-like members extending through a wall of said housing, each of said plurality of members being con-

nected in fixed relation to one of said stitch forming means, and connections within said housing from said drive shaft to each of said plurality of members for imparting stitch-forming movements to said members, said connections being arranged to impart bodily reciprocation to said needle and underlooper and a combined oscillation and bodily reciprocation to said overedge looper, the bodily movement of said overedge looper being more rapid toward one end of its stroke than toward the other.

16. An overedger comprising a frame having an enclosed, lubricant-tight housing, a main drive shaft extending through said housing and projecting therefrom at both ends, means mounted on one end of said shaft for driving the same, stitch-forming means comprising a needle, an underlooper and an overedge looper outside of said housing, work trimming mechanism including a movable trimmer blade adjacent the point of stitch formation, a plurality of shaft-like members extending through a wall of said housing, each of said plurality of members being connected in fixed relation to one of said stitch forming means and movable trimmer blade, and connections within said housing from said drive shaft to each of said plurality of members for imparting stitch-forming movements to said means and work trimming movement to said trimmer blade.

17. In an overedge sewing machine a needle reciprocated in a vertical plane containing the line of seam formation, an under looper, a rod carrying said looper and mounted for longitudinal reciprocation in a direction perpendicular to said plane, an overedge looper, a rod carrying said overedge looper and mounted for longitudinal reciprocation in a direction perpendicular to said plane and for oscillation about its axis, said overedge looper carrying rod being disposed above and in rear of said under looper carrying rod, a main drive shaft, and connections from said shaft for operating said needle and said rods in coordinated relation to effect overedge stitch formation.

18. In an overedge sewing machine having a horizontally disposed throat plate, a needle reciprocated in a vertical plane containing the line of seam formation, an under looper, a rod carrying said looper and mounted for longitudinal reciprocation in a direction perpendicular to said plane, an overedge looper, a rod carrying said overedge looper and mounted for longitudinal reciprocation in a direction perpendicular to said plane and for oscillation about its axis, said overedge looper carrying rod being disposed above said throat plate, a main drive shaft, and connections from said shaft for operating said needle and said rods in coordinated relation to effect overedge stitch formation.

19. In an overedge sewing machine a needle reciprocated in a vertical plane containing the line of seam formation, an under looper, a rod carrying said looper and mounted for longitudinal reciprocation in a direction perpendicular to said plane, an overedge looper, a rod carrying said overedge looper and mounted for longitudinal reciprocation in a direction perpendicular to said plane and for oscillation about its axis, a main drive shaft, and connections from said shaft for operating said needle and said rods in coordinated relation to effect overedge stitch formation, said connections being all disposed at one side of said vertical plane.

20. In an overedge sewing machine a needle

reciprocated in a vertical plane containing the line of seam formation, an under looper, a rod carrying said looper and mounted for longitudinal reciprocation in a direction perpendicular to said plane, an overedge looper, a rod carrying said overedge looper and mounted for longitudinal reciprocation in a direction perpendicular to said plane and for oscillation about its axis, said overedge looper carrying rod being disposed above and in rear of said under looper carrying rod, a main drive shaft, and connections from said shaft for operating said needle and said rods in co-ordinated relation to effect overedge stitch for-

16
mation, said connections being all disposed at one side of said vertical plane.
